(74) *Attorney, Agent, or Firm* — Birch, Stewart, Kolasch & Birch, LLP(57) **CLAIM**

The ornamental design for a display cabinet as shown and described.

DESCRIPTION

1. Display cabinet

1.1 : Top perspective view

1.2 : Front

1.3 : Back

1.4 : Left

1.5 : Top

1.6 : Bottom perspective view

1.7 : Top perspective view 2

1.8 : Top perspective view 3

1.9 : Top perspective view 4

1.10 : Top perspective view 5

The broken lines depict portions of the display cabinet that form no part of the claimed design; reproduction 1.1 is a top perspective view of the display cabinet; reproduction 1.2 is a front view thereof; reproduction 1.3 is a back view thereof; reproduction 1.4 is a left view where the right view is a mirror image; reproduction 1.5 is a top view where the

(Continued)

bottom view is a mirror image; reproduction **1.6** is a bottom perspective view thereof; reproduction **1.7** is a top perspective view showing the use state with bags displayed; reproduction **1.8** is a top perspective view showing the use state with the door open; reproduction **1.9** is a top perspective view showing the use state with the door open and the shutter door partially closed; reproduction **1.10** is a top perspective view showing the use state with the drawer comprising the control panel open while the door and the shutter door are completely open; this design is for a display cabinet that can display products such as bags; as shown in reproduction **1.7**, the door is made of a transparent glass material, so the displayed product inside can be seen from the outside; as shown in reproductions **1.9** and **1.10**, each shelf is separated into two parts, front and back, and an accordion-type shutter door that can be opened and closed is installed between them; so, a user can use the space divided into front and back; as shown in reproduction **1.10**, there is a drawer that can store various accessories within, and this design can store the bags and the like in the optimal condition by using the control panel at the front of the drawer; this design has lightings at the inside wall and the

lower part of the shelves and elsewhere, so that the products can be displayed in various ways.
